UNITED STATES PATENT OFFICE

160,523

EXTERNAL CASING FOR A BEVERAGE
PREPARING MACHINE

Glenn R. Oakmont, Los Angeles, Calif., assignor to Sof-Tee Corporation, Los Angeles, Calif., a corporation of California

Application December 12, 1949, Serial No. 6,567

Term of patent 7 years

(Cl. D44—1)

To all whom it may concern:

Be it known that I, Glenn R. Oakmont, a citizen of the United States, residing at Los Angeles, county of Los Angeles, State of California, have invented a new, original, and ornamental Design for an External Casin for a Beverage Preparing Machine, of which the following is a specification, reference being had to the accompanying drawing, forming part hereof.

Fig. 1 is a perspective view of the external casing for a beverage preparing machine, showing my new design.

Fig. 2 is a front elevation, and

Fig. 3 is a rear elevation.

I claim:

The ornamental design for an external casing for a beverage preparing machine, substantially as shown.

GLENN R. OAKMONT.
